J. O. SNYDER.
GASOLINE TURBINE.
APPLICATION FILED NOV. 30, 1915.

1,194,560.

Patented Aug. 15, 1916.

UNITED STATES PATENT OFFICE.

JAMES O. SNYDER, OF DECATUR, ILLINOIS.

GASOLENE-TURBINE.

1,194,560.

Specification of Letters Patent. Patented Aug. 15, 1916.

Application filed November 30, 1915. Serial No. 64,307.

To all whom it may concern:

Be it known that I, JAMES O. SNYDER, a citizen of the United States, residing at Decatur, in the county of Macon and State of Illinois, have invented certain new and useful Improvements in Gasolene-Turbines, of which the following is a specification.

This invention relates to internal combustion engines and has special reference to turbines driven by the explosion of a charge of gasolene or other hydrocarbon.

The object of the invention, generally stated, is to minimize the number of moving parts whereby the frictional resistance to the operation will be decreased and the speed and consequent power of the rotor obtained from a given charge will be increased.

More specifically stated, the object of the invention is to provide novel means whereby the velocity of the exploded gases in escaping from the compression and explosion chamber will be utilized by the impact of said gases to impart motion to the rotor.

Another object of the invention is to provide novel means whereby fuel will be continuously supplied and compressed and then exploded so as to act successively upon different points of the periphery of the rotor whereby to impart a continuous rotary motion thereto.

Other incidental objects of the invention will appear as the description of the same proceeds and the novel features will be particularly pointed out in the claim following the detailed description.

In the annexed drawing, I have shown a sectional elevation of an engine embodying the principles of my invention.

In carrying out my invention, I employ a rotor 1 and a housing therefor, indicated at 2, which may be of any desired construction and dimensions, the rotor being secured to a shaft 3 mounted in suitable bearings upon the casing and being so proportioned that the clearance between the periphery of the rotor and the inner circumference of the stator or casing will be just sufficient to prevent the rotor binding against the stator. The stator or casing is constructed with pluralities of ports 4 at various points around its periphery, which ports are disposed approximately tangential to the rotor so that the gases passing through said ports

will be directed against the vanes of the rotor and by their impact upon said vanes 55 will drive the rotor. Spaced from the ports 4 are outlet or exhaust ports 5 which may open to the atmosphere or lead into conduits or pipes by which the vapors may be conveyed to any desired point. In the present 60 instance, I have illustrated two sets of ports 4 but it is to be understood that a greater number of sets may be employed, the number depending upon the size of the engine and the work for which it is designed. In 65 order to successfully apply the principles of my invention, however, at least two sets of ports must be provided and each set of ports must register perfectly with the exhaust ports 6 in the side of a cylinder 7. Within 70 each cylinder 7 is mounted a piston 8 and the stroke of this piston should be so regulated that, when the piston is at the inner limit of its movement, its inner end will be directly over that port 6 nearest the adjacent end of the cylinder so that, when an 75 explosion occurs, the piston will at once uncover an outlet port and permit the gases to immediately flow to and against the rotor. A piston rod 9 extends from each piston 80 through the end of a cylinder and has its outer end supported by the end of a yoke 10 which is secured upon the end of the cylinder. Between the end of the yoke and a stop 11 on the piston rod is coiled a spring 85 12 which, by its expansion, tends to hold the piston over the ports 6. By placing the stops 11 at various points along the piston rod, the tension of the spring 12 may be adjusted so that any desired compression 90 may be obtained in the compression chamber. To arrest the inward movement of the piston and prevent injury to the stop 11 by forcible contact with the stuffing box 13, I provide a lighter spring 14 around the piston rod between the said stop and the end of the stuffing box. The cylinders, it will be noted, are arranged in series and that end of the cylinder from which the yoke 10 projects may be termed the charging end while 100 the opposite end may be termed the compression and explosion end, the charging end of one cylinder being connected with the explosion end of the other cylinder by a pipe or conduit 15. An inwardly opening valve 105 16 is mounted at the end of the pipe 15 so

as to permit flow through said pipe into the compression chamber and a similar valve 17 is mounted in the charging end of the cylinder to control the flow into the charging chamber. Each charging chamber is in communication with the carbureter through a supply pipe 18 which leads directly to the valve 17. A spark plug 19 is provided in the explosion end of each cylinder and this 5 spark plug may be of any preferred construction and will, of course, be connected with a timer and ignition system. The timer and ignition system, however, form no part of my invention and may be of any 10 well-known type. I have, therefore, deemed it unnecessary to illustrate the same in the present application.

Leading into each end of each cylinder is a priming supply pipe 20 through which 20 an initial charge may be fed into the cylinder from any convenient form of pump, the end of each of said pipes 20 being equipped with a valve 21 to permit flow into the cylinder and prevent flow therefrom.

25 The construction and arrangement of the several parts of my improved engine being thus made known, it is thought that the operation and advantages of the same will be readily understood and appreciated. When 30 it is desired to start the engine, a charge of fuel is pumped into each end of at least one cylinder and a charge is also pumped into the charging end of the other cylinder. Assuming that the cylinder shown at the 35 left in the drawing receives a charge of fuel in both ends and the cylinder shown at the right receives a charge only in the charging end, which in the present instance, is the lower end of the said cylinder, the charge 40 at the lower end of the left-hand cylinder will be under compression, the degree of compression being determined by the tension of the spring 12. A spark may be formed at the plug 19 by manually closing 45 a preliminary ignition circuit or otherwise sending a current through the spark plug and an explosion will thereby be caused in the left-hand cylinder. The force of the explosion will drive the piston in said cylinder 50 outwardly against the tension of the spring 12 and will immediately uncover the exhaust ports 6 so that the exploded gases will escape with great velocity and by their impact upon the vanes of the rotor will drive 55 the same. When the piston moves outwardly, the charge in advance thereof will be driven through the pipe 15 into the compression and explosion chamber of the right-hand cylinder while the charge at the 60 lower end of said cylinder will be forced through the lower pipe 15 into the cylinder in which the explosion has just occurred. Each charge in its travel will overcome the spring holding the valve 16 seated and will 65 also be slightly compressed against the

valves 17 and 21 so as to hold them seated. When the compression chamber of the right-hand cylinder has been fully charged, the gases therein will be under compression and an explosion will be effected in said chamber, the exploded gases escaping through the ports 6 and 4 to impinge upon the vanes of the rotor and propel the same in the manner previously described. As soon as the charge has been transferred from one cylinder to the other cylinder, the spring 12 70 will expand and drive the piston inwardly so as to create a partial vacuum between the piston and the valve 17 whereby the said valve will be unseated and a charge of fuel 75 drawn into the charging chamber from the carbureter. The charge which is in the explosion end of the cylinder is, of course, compressed. The previously described operation will then be repeated and will continue automatically until the supply of fuel 80 has been exhausted or is cut off by the manipulation of the throttle valve in a well-known manner. The timer and ignition system will be so arranged that the explosions 85 will occur in the several cylinders successively and, consequently, there will be a continuous application of power. When an explosion occurs in any one cylinder, the charge of the fuel in advance of the piston 90 in said cylinder will be driven into the next cylinder in advance and a charge will also be simultaneously drawn from the carbureter into the cylinder preceding the cylinder 95 in which the explosion occurs.

100 It will be readily noted that I have minimized the number of bearings necessary for the production of an engine inasmuch as the only bearings needed are two bearings to support the rotor shaft. The only other 105 moving parts are the pistons in the several cylinders and these pistons will move readily inasmuch as the power is not transmitted through the pistons and piston rods. The several valves employed may be of any 110 desired construction and as they have a very slight movement, the frictional resistance to be overcome at said places will be of no importance. The several cylinders are mounted directly upon the rotor casing and the 115 ports leading the gases from said cylinders are so disposed that the gases will impinge directly upon the vanes of the rotor and, consequently, will act upon the rotor practically simultaneously with the explosion. The several parts are evidently simple in 120 their construction and arrangement and an engine embodying the invention may be produced at a low cost while the up-keep will be upon an economical basis.

125 Having thus described the invention, what is claimed as new is:

The combination of a rotor, a rotor casing, a series of cylinders secured directly upon said casing, ports leading from the 130

several cylinders through the rotor casing to the rotor, pistons in the several cylinders dividing the same into explosion and charging chambers, means for establishing communication between the charging chamber of one cylinder and the explosion chamber of another cylinder, means for supplying an initial charge to each chamber of each cylinder, and other means for supplying the fuel to each charging chamber. 10

In testimony whereof, I affix my signature.

JAMES O. SNYDER.
